Joseph A. Briggs, Eriton, N. J., assignor to Radio Corporation of America, a corporation of Delaware

Application October 4, 1933, Serial No. 692,054

6 Claims. (Cl. 173—119)

This invention relates to telephones and more particularly to telephone transmitters or receivers of the electromagnetic type.

Heretofore, such apparatus has, in general, been of a very delicate and fragile nature; has required careful machining of the parts in order to secure proper adjustment and has not been capable of adjustment.

One of the objects of the present invention is to provide such a device which is extremely rugged and capable of withstanding severe shocks and blows.

Another object of the invention is to provide an improved adjusting means for the armature 15 of such a device.

Another object of the invention is to provide an improved means for firmly holding the armature in an adjusted position irrespective of shocks or blows which may be applied to the device.

Another object of the invention is to provide an improved means for accurately positioning the armature in relation to the pole pieces of the magnets and the actuating coil.

Referring now to the drawing:

Fig. 1 shows a rear view of the motor assembly of the telephone, looking toward the diaphragm.

Fig. 2 shows a vertical section through the unit perpendicular to the vertical axis of Fig. 1.

Fig. 3 is a detail view of the armature mounting and adjusting mechanism.

The entire motor mechanism shown in these figures is, of course, intended to be enclosed in the usual metal or composition case and to be provided with the usual type of ear piece or mouth piece for operating either as a telephone receiver or transmitter.

Referring first to Fig. 2, the device is provided with the usual diaphragm 1 which is mounted upon a supporting ring 2, forming the base of the motor unit.

The diaphragm is clamped against the member 2 by means of the retaining ring 3, which is provided with tongues 4, which are clinched over the edge of the member 2 to hold the diaphragm firmly thereagainst. The diaphragm is actuated by longitudinal movement of the driving rod 5, which in turn is actuated by the transverse vibration of the armature 6.

The driving motor of the device is of the polarized type and the laminated silicon steel members 7 constitute the pole pieces thereof.

These pole pieces are so shaped as to provide the proper clearance for the armature 6 at its outer end and so as to clamp the armature firmly therebetween at the inner end of the pole pieces.

The actuating coil 8 is situated in recesses of the pole pieces, as shown in Fig. 2, and currents passing therethrough cause the armature 6 to be attracted to one or the other pole pieces.

Appropriate magnets are placed in proper relation to the pole pieces 7 with the faces of the magnets in the location shown in dotted lines in Fig. 2, there being one substantially semi-circular cobalt steel magnet on each side of the pole pieces. A frame member 9 is secured to the base member 2 and projects rearwardly therefrom surrounding the magnets and providing a mounting for the armature and for the pole pieces.

Referring now to Fig. 3, the armature 6 is retained in an adjusting member 10, which is provided with a recess 11 having a width of about three times the thickness of the armature member 6, so that the spacing members 12 of bronze or similar material will fit snugly therein on each side of the armature 6.

It will be noted that the slot 11 is made so deep that only a comparatively small thickness of metal remains, the reason for which will hereafter appear.

The member 10 is provided with a semi-cylindrical face 13, through which the slot 11 is cut and which fits into the substantially semi-cylindrical recess in the member 9 and is held firmly therein by the cap screws 14. It will be noted that if both cap screws 14 are tightened, the member 10 will be flexed at the base of the recess 11 and will be thereby caused to grip the spacer members 12 to the armature very firmly.

While a tightening of one of the screws 14 and loosening of the other will cause an adjustment of the armature 6 about the center of curvature of the cylindrical surface 13, the ends of the bronze members 12 project into the gap between the lower ends of the pole pieces, as shown in Fig. 2, and are held firmly therebetween by pressure applied longitudinally of the said pole pieces by the bolts 15 and nuts 16 operating against the backplate 17, which abuts against the rear pole pieces and thereby forces both pole pieces firmly against base member 2.

The faces of the pole pieces 7, which abut against the bronze spacers 12, are curved on a slight radius to permit flexure of the armature therebetween. It will, therefore, be apparent that if, for example, the screw 14 adjacent to the diaphragm is tightened the member 10 will be rotated in a clockwise direction and will tend to rotate the armature 6 in the same direction; but due to the firm pivotal hold of the pole pieces 7 upon the members 12, the members 12 and the

armatures 6 will be flexed between the member 10 and the pole pieces, and the outer end of the armature will, therefore, be flexed in the opposite direction, i. e., toward the diaphragm.

5 As shown in Fig. 1, the frame member 9 is provided with a recess at 18 into which the bases of the pole pieces fit, and this recess is wide enough to accommodate also the keys 19, which are riveted to the sides of the said pole pieces, 10 the recess 18 being of a depth substantially identical with the height of the keys 19. Cover plates 20 are provided at each side of the recess 18 and are riveted firmly to the member 9 so as to provide a keyway in which the keys 19 fit quite snugly, this fit being substantially what is known 15 as a "press fit".

As shown in Fig. 2, the pole pieces 7 are provided with extensions adjacent to the keys 19 which abut against the members 12 on the armature 6. These extensions are of such length that the thickness of the members 12 and the member 6 is very slightly greater than the space which would exist between these extensions of the pole pieces with the nuts 16 tightened. Thus, when 25 the pole pieces are pressed into place, grasping the members 12 between them, and the nuts 16 are pulled tight and locked by the tongues on the lock brakes 22, it will be substantially impossible for any type of vibration or shock to 30 displace the relative positions of the several members, which will remain the same even though the device as a whole be somewhat deformed.

An appropriate screw 23 is provided for holding the entire motor unit, hereinabove described, 35 in a case of any usual construction, this screw, of course, being inserted through the back of the case and maintaining either the base member 2 or the tongues 4 against an appropriate rim or recess of the case.

40 Having described my invention, I claim:

1. A telephone motor comprising a vibratable armature, armature clamping means provided with a cylindrical surface, and means for adjusting the said clamping means about the axis of 45 curvature of said surface and simultaneously forcing said clamping means into intimate relation with the said armature.

2. A telephone motor comprising a vibratable armature, means clamping the armature at one end and having a cylindrically curved surface, and means for adjusting the said clamping means about the center of curvature of said surface 5 and flexing the clamping means toward the armature for retaining the said armature in said clamping means.

3. A telephone motor of the polarized type comprising a pair of laminated pole pieces each 10 provided with a pair of key members, a frame member provided with a keyway firmly fitting said key members and means for firmly clamping said pole pieces longitudinally of said keyway. 15

4. A telephone motor comprising a vibratable armature, means clamping the armature at one end and having a cylindrically curved surface, means for adjusting the said clamping means about the center of curvature of said surface and 20 flexing the clamping means toward the armature for retaining the said armature in said clamping means, and a driving rod connected to the free end of said armature.

5. A telephone motor comprising a vibratable 25 armature, means clamping the armature at one end and having a cylindrically curved surface, means for adjusting the said clamping means about the center of curvature of said surface and flexing the clamping means toward the armature for retaining the said armature in said clamping means, and means clamping the said armature laterally between the first said means 30 and the free end of the armature. 35

6. A telephone motor comprising a vibratable armature, means clamping the armature at one end and having a cylindrically curved surface, a member having a surface adapted to cooperate with said cylindrically curved surface, and means 40 holding said clamping means in engagement with said member for adjusting the clamping means about the center of curvature of said surface and firmly retaining said armature in said clamping means. 45

JOSEPH A. BRIGGS.
